UNITED STATES PATENT OFFICE.

ELIHU THOMSON, OF SWAMPSCOTT, MASSACHUSETTS, ASSIGNOR TO THE THOMSON-HOUSTON ELECTRIC COMPANY, OF CONNECTICUT.

ELECTRIC METER.

SPECIFICATION forming part of Letters Patent No. 448,894, dated March 24, 1891.

Application filed September 26, 1890. Serial No. 366,204. (No model.)

To all whom it may concern:

Be it known that I, ELIHU THOMSON, a citizen of the United States, and a resident of Swampscott, in the county of Essex and State 5 of Massachusetts, have invented certain new and useful Electric Meters, of which the following is a specification.

My invention relates to electric meters for use on either continuous or alternating current circuits; and it consists in certain details 10 of construction and combinations which in the main are more particularly applicable to meters wherein an electric motor is employed and the consumption is indicated or registered 15 by the speed of such motor.

One part of my invention relates to the construction of the commutator of the motor, the object being to insure reliability and regularity of action of the meter by eliminating 20 as far as possible the element of friction and the deterioration of the commutator-contacts or change of any character therein which would tend to change the resistance or make the action of the apparatus imperfect.

Another feature of my invention consists 25 in the introduction in that circuit of the motor wherein a constant strength of current should be maintained of an artificial resistance external to the motor and made large in proportion to the resistance of the motor itself. This feature of my invention is of 30 particular value when the armature and the field-magnet of the motor are traversed by separate currents, and the armature is made to carry the current of constant strength, the 35 field being excited by current varying with the consumption. The particular results accomplished by this feature of my invention will be referred to more in detail hereinafter.

My invention consists, also, in other features, to be more particularly hereinafter described, and then specified in the claims.

The meter to which I have shown the improvements constituting my present invention 45 applied is like that described in my prior application, filed August 26, 1889, Serial No. 321,988, and comprises, generally speaking, a motor traversed by the current for propelling or rotating a shaft or other mechanism which 50 operates a register and a retarder of the movement of the motor consisting of a closed

conductor in moving relation to a magnetic field, or vice versa.

In the drawings I have illustrated the meter as connected up in the manner preferable 55 when it is to be employed for measuring the consumption of energy on a constant potential circuit, although the mechanical features and constructions hereinafter described are applicable to electric motors generally, and 60 the resistance applied in the circuit of the meter might be employed when the meter is connected up in other ways or upon other circuits.

In the accompanying drawings, Figure 1 is a 65 perspective or isometrical projection of a meter having the general elements of construction described in my prior application before referred to, with modifications in the details constituting my present invention. Figs. 2, 3, 70 4, 5, and 6 illustrate parts of the commutating devices. Fig. 7 illustrates in vertical cross-section the bearings of the armature-shaft of the motor. Fig. 8 is a plan of the retarder mechanism modified in accordance 75 with my present invention. Fig. 9 shows in perspective the armature structure carrying the armature-coils and constructed in the manner preferred when the meter is employed for metering alternating currents. Fig. 10 is 80 a diagram illustrating one way of connecting up the circuits of the meter and the application to the meter of an artificial resistance in accordance with my invention.

Referring to Fig. 1, S is the shaft which 85 carries the armature A, constructed as hereinafter more particularly described, which armature revolves in a field produced by the action of two coils C C', the latter of which is here indicated in dotted lines. The movements of 90 the armature are registered or counted by a register R geared to such armature-shaft. The armature might be of the ring type, though it is preferred to make it, as indicated, with a set of coils wound somewhat after the fashion 95 of a Siemens armature, and connected to a commutator K, constructed in the manner to be presently described. The retarder D, carried by such shaft, consists of a disk of copper, which revolves past the poles of several 100 permanent magnets M, mounted on the base B of the machine.

One of the features of my present invention is the arrangement of magnets M in such way that the poles on the same side of the disk D shall alternate in polarity, as indicated 5 in Fig. 8—that is to say, the magnets are reversed in position as to their opposite poles, so that a magnet which has a north pole above and a south pole below the disk shall be followed, proceeding in the direction of revolution 10 of the disk, by one whose north and south poles are respectively below and above said disk.

For the purpose of varying the retarding effects produced by the traverse of the disk, 15 plate, or conductor D with relation to the poles of the magnet, I mount or support one or the other element of the device so that it may be adjusted with relation to the other in a plane parallel to the plane of movement, and 20 in such way as to change the speed of the traverse of one part past the other, thereby changing the strength of the induced or Foucault currents set up and varying the resistance to movement. Such adjustment may 25 be conveniently attained by pivoting one of such magnets, as indicated in Fig. 8, so that by swinging it on its pivot the distance of its poles from the center of the disk will be changed. By this adjustment a calibration 30 of the rotations of the motor-armature may be readily effected.

B' is an extension from the base B for supporting the artificial resistance-coil placed in the circuit of the motor, as hereinafter described, while P is the upper pivot for the shaft S, and J J are side standards from which the pivot and the register mechanism are supported.

In order to provide for transportation of 40 the apparatus without injury, I apply to the lower end of the shaft S an adjustable lifting and supporting device, such as indicated at P², Fig. 7, whereby the shaft may be lifted and supported off its pivot. The lower pivot 45 of the shaft S is indicated at P³, Fig. 7, while the lifter referred to is indicated at P², and is mounted as a nut upon a screw-standard carrying the pivot-bearing, so that by screwing up the lifter P² it may be brought into 50 engagement with a cup-shaped extension F, carried at the lower end of the shaft S, below the disk D. When supported by the lifter-screw P², engaging with such cup-shaped extension, the pivotal bearings of the shaft 55 are protected from injury, and lateral movement of the shaft and parts connected therewith during transportation is prevented.

One of the great obstacles to success in the 60 operation of electric meters having electric motors with a commutator has been the considerable friction which has heretofore existed at the commutator, as well as the variations in the friction and the development of imperfection in the commutator and variations of resistance thereat through the action 65 of the current and minute sparks on the commutator-surfaces.

One of the principal features of my present invention consists in the provision of means whereby a meter may be produced 70 which shall be entirely free from objections on this score, and which shall be reliable and constant in operation.

After a long series of experiments with many different materials and combinations 75 of materials I have ascertained that the results desired can be practically and successfully attained only by the use of pure silver for the bearing or contact surfaces of the revolving segments of the commutator and the 80 brushes bearing on the same. To reduce the initial friction to the smallest possible point, the commutator-cylinder should be made of as small a diameter as is practicable, the contact-brushes being made to bear thereon with 85 an extremely light pressure. This extremely light pressure becomes possible by the use of pure silver for the commutator, since the electric currents may be passed through it without burning and without deterioration. 90 I have found by experiment that silver used in this manner does not corrode or form a film of non-conducting oxide in the air. Hence the effect of slight sparking at the 95 commutator is small, there being in substance no oxidizing effect, or, rather, the effect of the heat produced being to reduce the oxide back to the pure silver. Owing to the fact that silver is an excellent conductor of heat, any heat developed is rapidly carried off from the 100 contacts and dissipated. A further advantage is that the metal is readily obtained in a pure state and is the best known conductor of electricity.

It is not sufficient for the purposes of my 105 invention to make one part only of the commutator of silver and to use another metal for the other portion. Platinum I find to be unsuitable for the purposes, owing to the fact that the contacts are spoiled by the deposition of platinum black when sparks are formed, the substance being a non-conductor to almost the extent of platinum oxides. For the same reason I have found it impossible to make a meter which shall be practicable 110 when copper is employed for the contacts, owing to the fact that copper oxidizes and does not remain bright, especially when there is a slight sparking. The difficulty from oxidation might be gotten rid of by employing gold; but such material is not suitable, first, because of its expense; secondly, because it is a poor conductor, and, thirdly, because it is more difficult to work in a pure state. Platinum, though easily worked, 115 is a poor conductor, and is found to be unsuitable for the reasons above stated. Besides introducing an electrical resistance, which is undesirable, the platinum dust produced when platinum is employed for the 120 commutator causes an increased mechanical friction of the surfaces. This difficulty I find to be entirely absent when silver is employed, the coefficient of friction of silver being prac- 125 130

tically the same during motion as at starting. Other experiments made by me on the use of copper with carbon, or of carbon for both parts of the commutator, gave results that were not satisfactory, the meters when subjected to trial either breaking down after running for a greater or less length of time or failing utterly to yield uniform results, and it was clearly demonstrated that it was futile to work with the substances ordinarily employed for commutators of electric motors, and that only by the employment of silver could good results and uniform work be secured. I find that it is also very desirable to construct the commutator K of the motor of just as small diameter as possible. In fact, as near the diameter of the shaft or spindle upon which it is carried as it is possible to make it and maintain the insulation of the commutator-segments from the shaft. By resorting to this feature of construction I avoid a difficulty which has been heretofore met with — to wit, the element of friction, which element, if too large, would render the meter altogether inoperative on small loads.

The details of the commutator are illustrated more fully in Figs. 2 to 6, inclusive. To construct such a commutator I preferably proceed as follows: T, Fig. 2, is a silver tube, which may be a drawn tube, and which is taken and divided by longitudinal slits, as indicated in Fig. 3, which stop short of the ends of the tube, as indicated, and divide the same into the required number of segments for the commutator. Such a tube is taken and forced upon the armature-shaft S, Fig. 4, a thin layer of insulation (shown in black in the figure in exaggerated thickness) being interposed between the tube and the shaft. The segments are now bound down upon the shaft by means of two encircling bands, indicated in Fig. 5, which are of insulating material, or of conducting material lined with insulating material. The segments are by this means fastened in place, after which the ends of the cylinder are cut off, leaving a series of segments insulated from one another and held together by rings on an insulating-support encircling the shaft closely. The ends of the segments or strips to which the armature-wires are to be connected may be bent away from the shaft, as indicated in Fig. 5. It is obviously not necessary to leave both ends of the tube unslit, since the proper relative position of the segments prior to the binding of them upon the shaft will be preserved in a measure if one end only were left unslit. It is best, however, to leave both ends unslit, since the segments are thereby kept more rigidly in their proper relative position during the construction of the commutator.

The brushes indicated in Fig. 8 may consist of pieces of spring metal shod at the end with little plates of silver, or they may be made entirely of silver, as is obvious. They should be constructed to bear upon the commutator with an extremely light pressure.

If the meter is to be used for alternating and direct current measure interchangeably, it is obvious that the construction must be special to the case, and for this purpose I wind wire only without iron cores to be magnetized, thereby leaving simply an air-field to be produced by the field-coils and to be acted upon by the armature-currents in producing rotation.

To receive the coils of the armature, I construct a hollow frame, (exhibited in Fig. 9 and consisting of two insulated disks or disks of insulating material Q Q,) placed at a distance apart on the shaft S and having polygonal outlines, preferably for ease of winding the armature-coils. The projecting pieces at the angles of the polygonal surfaces separate the coils during the winding operations and can afterward be removed or cut down. These disks are preferably separated by a few insulating-pillars, which, however, might be made of brass or other non-magnetic metal, and which are indicated at V V. The outside of this structure is now covered by winding coils, as shown, one coil alone being seen in the figure, the other coils making an angle with the coil shown, and wound in the manner of a Siemens armature, and all of the coils being connected into closed circuit. Of course it is necessary that each face be occupied by two coils in such a winding, or at least that the spaces be in pairs, so as to complete the closed circuit, as is well known. I thus secure a hollow frame, which enables the coils to be mounted and ventilated, and which gives slight spaces between the coils, so that no effects of increased temperature by the current flowing is felt, and the coils are made of very fine wire compactly placed, so as to get the greatest electrical work out of them, taking into consideration the absence of any iron core in their interior. The armature-coils A, then, and the field-coils themselves produce what may be called "air-magnets," reacting upon each other to give rotation to the structure.

In Fig. 10 the meter described is shown applied to a circuit a b, on which electric lamps L L or other devices are operated in parallel, such circuit being one which supplies a current of approximately constant potential to said devices. The field-exciting coils C C' of the motor are included in the main electric circuit with the translating devices, as shown, so that the strength of the field will vary with the consumption of energy on the circuit. The electric armature A is in a branch of high resistance across the mains, as indicated, so that it will, when normal and proper action of the meter takes place, be traversed by current constant in amount. This relative arrangement of the parts in the circuit is claimed in my prior application before referred to. W is an artificial resistance in the circuit of the armature, but external thereto, and made high in amount, so as to limit the current and avoid the necessity for

winding the armature of extremely-fine wire to stand considerable potential. By making this resistance very high in proportion to the armature-resistance, a practically-constant current in such armature under conditions of change of speed is attained, owing to the fact that the variations of resistance and counter electro-motive force in the armature itself will be so small in proportion to the total resistance as to be practically negligible. The high resistance W will therefore also have an important function in practically abolishing any variations in the action of the motor arising from any change of resistance at the commutator-contacts, and will for this and the reason above noted add greatly to the regularity of action of the motor.

In the case of a meter operated by alternating electric currents this resistance, which is external to the armature, is wound so as to have practically no self-induction, and being made, as described, so as to constitute the greater part of the total resistance in the circuit, the feature of self-induction as a modifier of the registry may be practically eliminated.

What I claim as my invention is—

1. The combination, in an electric meter, of an electric motor, a register mechanism for counting the movements of said motor, and a commutator for said motor, having both its moving and stationary conducting-surfaces made of pure silver, as and for the purpose described.

2. In an electric meter, an electric motor having a commutator the brushes and segments of which are both made of pure silver, as and for the purpose described.

3. In an electric meter, an electric motor having its commutator constructed of as small diameter as practicable and from some non-oxidizing material, in combination with commutator-brushes of non-oxidizable material bearing thereon with light pressure, as and for the purpose described.

4. The combination, with the armature shaft or spindle S , of the commutator-cylinder consisting of a number of strips of thin sheet metal fastened directly upon a thin layer of insulating material encircling the shaft and having their free ends bent outwardly for attachment of electric conductors.

5. The herein-described improvement in constructing commutators, consisting in slitting a tube longitudinally by slits extending a sufficient distance to complete the separate commutator-segments, leaving one or both ends of the tube unslit, thereby completely forming the desired number of commutator-segments, binding the slit portion of the tube at or near both ends down upon the shaft over an interposed layer of insulating material, and then cutting off the unslit end or ends.

6. The herein-described improvement in constructing commutators of small diameter,

consisting in taking a tube of greater length than necessary to form the complete commutator, dividing the same by longitudinal slits sufficient in length to complete commutator-segments of the desired width in the direction of its axis, leaving at one end of said tube an unslit portion, applying the tube thus formed to the commutator spindle or shaft over an interposed continuous layer of insulating material, applying binding-rings over the tube at its slit portion and near the opposite ends of the slits, and then removing the unslit end, as and for the purpose described.

7. The combination, in an electric meter, of a retarder consisting of a closed conductor in moving relation to a magnet adjustable, as described, so as to change the distance of the poles of such magnet from the center of the movable disk.

8. The combination, in an electric meter, of a retarding mechanism consisting of a disk or plate of copper and a magnet in moving relation to one another, one of said parts being adjustable in a plane parallel with the other for the purpose of changing the relative speed of traverse of the one part with relation to the other, and thereby varying the retarding effect.

9. The combination, with the retarding disk or plate D , of a pivoted magnet M , adapted to swing in a plane parallel with the plane of the disk.

10. In an electric meter, the combination, with a motor and a registering mechanism, of a retarding device consisting of a plate or conductor and a series of magnets the poles of which embrace the plate and alternate in polarity, as and for the purpose described.

11. In an electric meter, a motor-armature structure consisting of two disks of insulating material, having polygonal outline and fastened together by pillars of non-magnetic material, and electric coils wound over such disks with ventilating-spaces between the coils, as and for the purpose described.

12. In an electric meter, the combination, with an electric motor and a register for counting the movements thereof, of an artificial resistance external to the motor and placed in the circuit of such motor wherein a constant current is to be maintained, such resistance being the larger part of the total resistance of such motor-circuit.

13. The combination, with an electric meter operated by alternating currents, of a non-inductive artificial resistance placed in that portion of the meter-circuits wherein a constant current is maintained and made to form the larger part of the resistance of said circuit.

14. The combination, with an electric motor operated by alternating currents, of a register for counting the movements of said motor, and a non-inductive artificial resistance external to the motor and placed in the meter-circuit including the armature and commu-

tator, such artificial resistance being made large in proportion to the resistance of the normal resistance of the armature and commutator.

5 15. The combination, in an electric meter, of an electric motor having its field traversed by current varying with the consumption and an armature for such motor placed in a constant-current circuit, in combination with an artificial resistance placed in the armature-circuit external thereto.

10 16. The combination, substantially as described, of an electric-motor field-coil, an electric-motor armature-coil provided with a commutator and placed in an alternating-current circuit, including a non-inductive resistance external to the armature and commutator, as and for the purpose described.

15 17. In an electric meter for measuring alternating electric currents, the combination,

with that part of the motor which is included in a constant alternating-current circuit, of a non-inductive resistance external to such part of the motor and made large in amount in proportion thereto.

25

18. In an electric meter, the combination, with the armature-shaft, of a cup-shaped extension at or near the lower end thereof and a screw-support P^2 , consisting of a nut upon a screw-standard which carries the pivot-bearing for the shaft, as and for the purpose described.

30
